UNITED STATES PATENT OFFICE.

HARRY T. LALLY, JR., OF ALAMEDA, CALIFORNIA.

TOILET-BOWL.

1,254,609.

Specification of Letters Patent. Patented Jan. 22, 1918.

Application filed May 17, 1916. Serial No. 98,192.

To all whom it may concern:

Be it known that I, HARRY T. LALLY, Jr., a citizen of the United States, residing at Alameda, in the county of Alameda and 5 State of California, have invented certain new and useful Improvements in Toilet-Bowls, of which the following is a specification.

This invention relates to toilets and has 10 as its principal object the construction of a bowl which is novel in form, sanitary in use and is less liable to become soiled than the present type of bowls.

Another object of my invention is to provide 15 an improved form of seat to be used on the bowl.

With these and other objects in view my invention consists in the novel arrangement and construction herein described and more 20 specifically pointed out in the appended claims.

Reference being had to the accompanying drawing,

Figure 1 is a view in perspective showing 25 a bowl constructed in accordance with my invention.

Fig. 2 is a view in section through the upper part of the improved bowl showing the seat positioned thereon.

30 Fig. 3 is a view in plan showing the bowl with the seat cover partly broken away.

Referring to corresponding parts by the same numerals of reference, 1 denotes the bowl having the base flange 2 and roll rim 35 3. This rim is provided with the water channel 9 from which are small openings 10 to allow the water to spray the inner surface of the bowl.

The front part of this rim is extended forwardly as shown at 4 making the bowl 40 longer at this point than the usual bowl. At the back the roll-rim is curved upwardly as at 6 and then rearwardly a short distance and across the extension 7. This provides 45 a recess 5 substantially rectangular in shape the rear surface 5' of which is considerably higher than the underside of the rim over the rest of the bowl.

The extension 7 is provided with the 50 opening 11 in which the water supply pipe is attached and from which extends a channel 9' to the channel 9 in the rim and another channel 12 to the bottom of the bowl. The rim around the recess 5 is also provided with

openings 10 permitting the surface 5' to be 55 thoroughly flushed.

Each side of the extension 7 is provided with ears 8 adapted to receive the hinge connections. The seat consists of two arc-shaped pieces 13 which meet neither at the 60 front nor back. At the front a metal piece 14 is provided which connects the two forward ends and holds them in rigid relation. To the rear ends of each of the seat pieces is attached the hinge member 17. This member is pivotally attached to the bolt 16 which in turn is held in one of the ears 8. The cover board 15 is made in one piece and is provided with a rearward extension 19 to fit in the recess 5. The cover has secured to 65 it hinge members 18 which are in turn pivotally attached to bolt 16. It will be noted that the axis on which the hinge members 17 and 18 are movable, is back of the rear edge of extension 19 so that when the cover 70 is raised the movement causes this edge to clear the rim.

In use, lid is of course raised and the recesses at the front and back prevent soiling of the inner surface. The rim is also not 80 liable to become soiled due to the fact that at both the front and back it is recessed. At the back should any soiling take place on surface, 5' is flushed off in the regular manner.

I have thus provided a toilet which effectively accomplishes the objects outlined at the beginning of this specification, and yet is simple in construction. While I have shown the preferred embodiment of my invention it will be understood that changes 90 may be made in minor details and features of design without departing from the spirit of the invention.

What I claim as new and wish to cover by 95 Letters Patent is:—

1. A toilet bowl, a roll rim around the upper edge of said bowl, said rim being curved upwardly and rearwardly and provided with a recess at the back of said bowl, the rear 100 surface of which is above the plane of the bottom of the main portion of the rim, and a pivotally supported lid having a tongue extending into said recess.

2. A toilet bowl, a roll rim around the upper edge of said bowl, said rim being curved to form recesses at the front and back of 105 said bowl, a seat comprising two parts sep-

arated at the front and back, a lid, a tongue on said lid extending into said back recess, and a hinge connection for said seat and said lid.

5. A toilet bowl, a rearward extension having its upper surface above the top of said bowl, a recess extending from said bowl into said extension, said rim extending

around the edge of said recess, a cover having a tongue extending into said recess, laterally extending lugs formed on the sides of said extension, and hinge connections for said cover attached to said ears. 10

In testimony whereof I affix my signature.

HARRY T. LALLY, JR.
